UNITED STATES PATENT OFFICE.

WILLIAM P. TAYLOR, OF BUFFALO, NEW YORK.

CARBURETOR.

Application filed June 10, 1922. Serial No. 567,376.

My invention relates to improvements in carburetors, and is concerned more particularly with the means for automatically controlling the supply of gasoline.

5 One of the objects of my invention is to provide a carburetor in which the fuel-supply opening is controlled by a fuel valve, and this opening reduced in size after the engine, to which the carburetor is connected, reaches 10 a pre-determined high speed.

Another object of my invention is to provide a carburetor with controlling mechanism whereby the speed of the engine to which the carburetor is connected may be limited to any 15 desired degree.

With the above and other objects in view to appear hereinafter, the invention consists in the novel features of construction and in the arrangement and combination of parts to 20 be hereinafter described and more particularly pointed out in the subjoined claims.

In the drawings:

Fig. 1 is a central vertical section through a carburetor, showing my invention embodied 25 therein in what I now consider its preferred form.

Fig. 2 is a plan view of the carburetor.

I have designated the carburetor, considered as a whole, by the numeral 7, and in the 30 selected type shown, it is combined with a gasoline container 8. The carburetor comprises a casing 9 extending diametrically across the top of said gasoline container and a cylinder 10 surmounting the carburetor casing 35 and having an inwardly-extending stop lug 11 thereon. The intermediate portion of the casing may be considered the carbureting chamber, which I have designated by the numeral 12, and this chamber is separated from 40 the interior of the cylinder 11 by a wall 14 in which a rotatable valve 15 is located having an opening or port 16 therethrough. When said opening or port 16 is in normal position it serves as a suction opening and connects 45 the carbureting chamber 12 with the interior of the cylinder 10.

17 designates the inlet of the carburetor casing, and 18 the outlet thereof. Within the carburetor casing near the inlet 17 thereof 50 is a butterfly or choke valve 19.

The rotatable valve 15 is located in the wall 14, and it has a shaft or stem extending out through the side of the carburetor to which a lever 21 is secured, the free end of 55 which is pivotally connected to one end of a link 22, the opposite end of which has pivotal

connection with the actuating lever 20 on the shaft of the butterfly or choke valve 19.

The outlet 18 is provided with the usual throttle valve 23, and the carburetor casing 60 has a depending portion 25 arranged centrally thereon, which is adapted to extend into the gasoline or other liquid hydrocarbon container 8 and be attached to the lower wall thereof, as at 26, or otherwise. The carbureting chamber 12 is depressed centrally, as at 65 27, and in this depressed portion a gasoline well 28 is arranged, said well opening directly into the carbureting chamber 12 and being in communication with the interior of the gasoline container 8 by a passage 29, preferably flared at the well, as at 30, for a purpose to appear hereinafter. The gasoline within the gasoline container 8 is maintained at a constant level by a float 31 in the usual manner. 70

The upper end of the cylinder 10 is open, and adapted for vertical movement in the same is a piston 32 which is hollow and preferably in the form of an inverted cup. 75

Screwed axially through the head 33 of 80 said piston is an externally threaded sleeve 34, which may have a flanged lower end within the piston and a polygonal upper end outside of the piston adapted to have a wrench or other tool applied thereto for rotating said sleeve and adjusting the same within the head of the piston. Screwed onto said sleeve 85 is a lock nut 35, which bears against the upper face of the piston and is adapted to lock the adjusting sleeve in adjusted position. The bore of said sleeve is threaded and a needle or fuel valve 36 is arranged adjustably within 90 said threaded bore, said valve having a sliding fit through the wall 14 separating the cylinder from the carbureting chamber 12. The upper end of this needle valve is provided 95 with a knurled head 37 by means of which the valve may be adjusted, the lower end of said valve being tapered or pointed, as at 38. The peripheral face of this pointed lower end is adapted for co-action with the flared face 30 at the upper end of the passage 29 so that a minute adjustment between said flared face and the pointed lower end of the valve may be effected. 100

Interposed between the flanged lower end of the sleeve 34 and the wall 14 and surrounding said needle valve is a coil spring 39 which serves to maintain the piston at its highest point against the stop lug 11. 105

As it may be necessary at times, and particularly in cold weather, to close or partly

close the choke valve 19 when starting the engine, it is of advantage to prevent the suction created within the carbureting chamber acting on the piston 32, and for this reason 5 I have provided the operative connection, hereinbefore described, between the rotatable valve 15 and said first-mentioned choke valve to close the suction opening 16 through said rotatable valve, which will, in such cases, prevent 10 the lowering of the needle valve for the purpose of reducing the supply of gasoline to the carbureting chamber until after the engine has been started and the choke valve again opened.

15 When first adjusting the carburetor for use, the needle valve 36 is moved into a position to allow gasoline to be fed into the well 28 where it is maintained at the level of the gasoline in the container 8. This adjustment 20 of the needle valve may, by chance, be proper for effective operation of the engine, but whether or not such is the case, can only be determined by running the engine under different conditions, the pumping action of 25 which will create suction within the carbureting chamber and lift the gasoline from the well 28. The gasoline in the well will become consumed and the natural flow of gasoline through the passage 29 will then provide sufficient fuel at the outlet of said passage to 30 keep the engine running. While the engine is running, the throttle valve 23 is opened to permit the engine to attain the speed which may be desired for a maximum, and with the 35 spring compressed under these conditions the fuel valve will be adjusted to feed the least amount of fuel for satisfactory operation. If the adjustment of the spring is not proper for the desired maximum speed of the engine, 40 the adjustment of this spring is made at this time, and when speeding the engine to the desired point, it is found that the piston 32 is moved downwardly to a degree to slightly close the outlet of the passage 29, the pressure 45 of the spring will be determined. Closing the throttle valve for idling of the engine, or for slow speed, will result in the piston rising and the fuel valve opening the outlet of the passage 29, and under these 50 conditions the proper supply of gasoline will be furnished in accordance with the depression in the carbureting chamber.

It is to be understood that the sleeve 34 may be rotated to adjust the compression of 55 the spring 39, and that the needle valve 36 may be adjusted independently while holding said sleeve against rotation, thus making it easy to effect any desired adjustment of the spring independently of the needle valve, or 60 any desired adjustment of the needle valve independently of the spring. It will be apparent therefore that when the needle valve

is adjusted, the maximum speed of the engine will be at its lowest when the compression of the spring 39 is adjusted to least 65 resistance, and will be comparatively higher as the compression of the spring is increased; this being due to the fact that the greater the resistance the spring has to the downward movement of the piston 32, the greater will 70 be the suction required in the cylinder 10 to lower said piston, and as the depression in said chamber increases with the speed of the engine and reaches a certain degree under normal running conditions, the piston will be 75 drawn downwardly and slightly close the outlet of the passage 29; the extent of such closing action depending upon the pressure to which the spring is adjusted.

It is, of course, to be understood that, while 80 I have shown a particular form of carburetor, the illustration of the same is used solely to make clear the operation of my improved mechanism for automatically controlling the supply of gasoline; and that my invention 85 may be applied to any form of carburetor having an air inlet, a mixture outlet and means to carburet air passing from the air inlet to the mixture outlet; also that it is not 90 the purpose of this specification to restrict myself to the use of gasoline, since any volatile liquid suitable for the purpose may be substituted therefor.

Having thus described my invention, what I claim is:—

1. A carburetor having a carbureting chamber, an air inlet and a mixture outlet, a cylinder in communication with said carbureting chamber, a spring-retained piston in said cylinder adapted to be actuated under suction created within said carbureting chamber, a fuel valve actuated by said piston, a choke valve in said air inlet, and means operatively connected with said choke valve to close communication between said carbureting chamber and cylinder when closing said choke valve.

2. A carburetor having an air inlet, a mixture outlet, a carbureting chamber between the two and a cylinder separated from said carbureting chamber by a wall, a rotatable valve in said wall having a suction opening therein, a piston within said cylinder, a valve connected to said piston to regulate the supply of gasoline to the carbureting chamber, means for keeping said piston at the end of its movement in one direction, a choke valve within said air inlet, and operative connection between said choke valve and said rotatable valve to cause the suction opening in said rotatable valve to be closed when closing said choke valve.

In testimony whereof I affix my signature.
WILLIAM P. TAYLOR.
